Primary Examiner—Marianne Pandozzi*(74) Attorney, Agent, or Firm*—Panitch Schwarze Belisario & Nadel LLP(57) **CLAIM**

The ornamental design for a percolator, as shown and described.

DESCRIPTION

FIG. 1 is a perspective view of a percolator in accordance with a first preferred embodiment of our new design;

FIG. 2 is a left-side elevation view thereof;

FIG. 3 is a front elevation view thereof;

FIG. 4 is a right-side elevation view thereof;

FIG. 5 is a rear elevation view thereof;

FIG. 6 is a top plan view thereof;

FIG. 7 is a bottom plan view thereof;

FIG. 8 is a perspective view of a percolator in accordance with a second preferred embodiment of our new design;

FIG. 9 is a left-side elevation view thereof;

FIG. 10 is a front elevation view thereof;

FIG. 11 is a right-side elevation view thereof;

FIG. 12 is a rear elevation view thereof;

FIG. 13 is a top plan view thereof; and,

FIG. 14 is a bottom plan view thereof.

The broken lines in the figures are for illustrative purposes only and form no part of the claimed design.
